(57) **CLAIM**

The ornamental design for a substance applicator, as shown and described.

DESCRIPTION

FIG. 1 is a top front perspective view of a substance applicator, showing my new design;

FIG. 2 is a top rear perspective view thereof;

FIG. 3 is a front elevation view thereof, the rear elevation is a mirror image thereof;

FIG. 4 is a right side elevation view thereof;

FIG. 5 is a left side elevation view thereof; and,

FIG. 6 is a top plan view thereof, the bottom plan view is a mirror image thereof.

The dot-dash-dot broken lines shown in the drawings depict the bounds of the substance applicator, and the dot-dash-dot broken lines form no part of the claimed design.
